UNITED STATES PATENT OFFICE.

STEPHEN W. WOODWARD, OF BUFFALO, NEW YORK.

IMPROVEMENT IN COAL-SCREENS.

Specification forming part of Letters Patent No. **138,355**, dated April 29, 1873; application filed December 31, 1872.

To all whom it may concern:

Be it known that I, STEPHEN WALTER WOODWARD, of Buffalo, in the county of Erie and State of New York, have invented certain new and useful Improvements in Screen-Operators for Screening and Sifting Coal-Ashes, Flour, Sand, &c., of which the following is a specification:

This invention relates to screens or sifters for sifting coal, ashes, flour, &c.; and consists in attaching to a wire-cloth or other screen a system of levers, &c., for form of a "toggle" or "knuckle" joint, to oscillate said screen, as hereinafter described.

In the drawing, Figure 1 is a perspective view. Fig. 2 is a sectional side elevation.

A is an oblong box, having a shorter box, B, sitting therein. This box B has a wire-cloth screen, *a*, which forms its bottom, and is supported in place by side pieces attached to the inside of the outer box A. These supporting-pieces have small rollers or casters *b*, (see Fig. 1,) to enable the box B to work more easily in its movement back and forth. Attached to one corner of the outer box A is a pin or rod, *c*, which passes through and acts as a guide to bend strip of metal *d*, as shown. One end of this strip *d* passes through the box A, and is attached loosely to one corner of the screen-box B (see Fig. 2) in such a manner that it can be readily detached to allow the box B to be removed, as indicated by dotted lines at *e*. The other end of this strip *d* is riveted loosely to a longer strip, *f*, which, in turn, is riveted, at *g*, to a similar strip, *h*, which is pivoted, at *i*, to the side of box A, thus forming a "toggle" or "knuckle" joint by the bars *f* and *h*. It will be readily seen that if these bars are moved up and down by the rivet *g*, the box B will be moved backward and forward by the strip *d*.

There is a number of methods by which the bars *f* and *h* may be operated. One method is by extending the bar *h* backward in the form of a handle, as at C, by which means the screen may be readily and easily oscillated. Another method is by means of a crank motion. This I accomplish by attaching to the bars *f* and *h* a slotted metal piece, D, shown in Fig. 2, and having small slots *k*, where it is

secured to the bars *f* and *h*, to allow of sufficient play in its motion up and down. E is an upright post or standard secured to the base-piece H of the box A, and having a shaft passing through its top part, carrying two cranks, I and J, the former of which has a slide, *m*, working loosely in the slot in the piece D, while the latter or shaft J is provided with a handle, *n*, to operate the device.

The action of this arrangement will be seen at a glance. The cranks, in their revolutions, serve to raise and lower the piece D, which carries with it the bars *f* and *h*, and so operates the screen in precisely the same manner as by the handle C.

The advantages of this arrangement are many. I obtain two oscillations of the screen by only one revolution of the crank on one movement of the lever C, which is a great advantage, causing the screen to do its work in much less time, and by less use of power, as by the arrangement of the levers and bars I obtain a great purchase and a powerful leverage.

For sifting coal-ashes, &c., the box A will be made with a circular strip, *p*, attached to its bottom to fit into and hold the box upon a barrel; or it may be made with a larger box or reservoir to catch the ashes, &c.

There are many other methods by which the levers may be operated, but I prefer one of those shown.

It may also be applied to the screens of grain-separating machines.

What I claim as my invention is—

1. The toggle-levers *f* and *h*, in combination with the bent arm *d*, slotted piece D, and cranks I J, or their equivalents, for imparting a reciprocating motion to sieve B, substantially as described.

2. The combination of the bent piece *d* and screen-box B, when constructed, as shown and described.

In witness whereof I have hereunto signed my name in the presence of two subscribing witnesses.

STEPHEN W. WOODWARD.
